PISTON FOR ENGINE-CYLINDERS.

1,388,279.

Specification of Letters Patent. Patented Aug. 23, 1921.

Application filed October 29, 1920. Serial No. 420,360.

To all whom it may concern:

Be it known that I, CHARLES A. MARIEN, a citizen of the United States, residing at St. Louis, State of Missouri, have invented 5 certain new and useful Improvements in Pistons for Engine-Cylinders, of which the following is a full, clear, and exact description, reference being had to the accompanying drawings, forming a part hereof.

10 The present invention is directed to improvements in piston construction, and particularly to pistons intended for use in internal combustion engines. One of the objects sought is to make use of pistons cast 15 from aluminum or its alloys to secure lightness, and at the same time secure a fit between the piston and walls of the cylinder that will not only arrest or prevent side-slapping of the piston but will insure against 20 the passage of any oil past the piston into the combustion chamber of the engine. As well understood in the art, aluminum (and its alloys) has a comparatively high coefficient of expansion, so that an ordinary 25 aluminum piston in an internal combustion engine must when cold, fit with considerable looseness in the cylinder to allow for subsequent expansion by the heat of the gases to which the piston is exposed while the engine is running. When operating at a high 30 temperature (as a result of high speed) the piston by reason of expansion may of course maintain proper contact with the walls of the cylinder; but when the temperature drops 35 (as when running at low speed) the contraction of the piston allows so much clearance between it and the cylinder walls as not only to cause side-slapping, but at the same time permit a flow of oil past the piston (and 40 packing rings) into the combustion chamber and thus give rise to engine trouble. On the other hand, if an aluminum piston has the desired fit when cold, it will bind against and cut or score the cylinder walls when heated, 45 and thus interfere with the free operation of the engine. With my improvement I not only avoid side-slapping of the piston but insure against the passage of oil into the combustion chamber under all working conditions by providing the skirt of the piston 50 with a series of longitudinal slits and resilient skirt sections between the slits, said resilient sections being maintained in permanent and proper working engagement 55 with the cylinder walls by the outward

spring of the metal, the necessary rigidity being imparted to the skirt by a series of longitudinally slit tubular metallic filler strips inserted into suitable cylindrical enlargements of the slits of the skirt, said strips permitting the skirt to expand and contract both radially and circumferentially with any changes of temperature to which the piston is subjected. The advantages of my improvement will be fully apparent from 60 the following detailed description in connection with the accompanying drawings in which—

Figure 1 represents a middle longitudinal section through the cylinder and crank case 70 of an internal combustion engine, showing my invention applied thereto; Fig. 2 is a half elevation and half middle longitudinal section of a piston showing the invention on a larger scale; Fig. 3 is an end view of the 75 piston on the side facing the crank-case; Fig. 4 is a longitudinal sectional detail on the line 4—4 of Fig. 3; Fig. 5 is an enlarged cross-sectional detail on the line 5—5 of Fig. 2; and Fig. 6 is a perspective of one of the 80 resilient split filler tubes detached.

Referring to the drawings, C, represents the cylinder, C', the crank-case, P, the piston, and R, the connecting rod coupling the piston to the crank-arms A, as well understood in the art. The upper portion of the piston is provided with any conventional form of packing ring 1 (three rings being shown in the present example), the lower portion or skirt of the piston (the portion 85 nearest the crank-case) being provided with annular peripheral oil-distributing grooves 2 from which lead ducts 3 to the interior of the piston to return any excess oil back to the crank-case. These features I do not 90 claim as they form no part of my invention, the latter being concerned with the slitting of the skirt and the manner of imparting rigidity thereto to prevent side-slapping of the piston.

In the form of the invention, as shown, the skirt of the piston is formed with a plurality of longitudinally disposed parallel slits 4 (four in the present example), said slits extending from a point substantially 95 opposite the piston pin 5 (inserted through the openings O of the bosses 6) to the free end of the skirt (Fig. 1), the walls of the skirt at the slits being reinforced on the inside by ribs 7. The walls of the slits 4 100

- are formed with the central tubular or cylindrical enlargements 4', said enlargements receiving the longitudinally slit, resilient metallic filler tubes 8, one of the longitudinal edges of the tube adjacent the slit 4 thereof being formed with an outwardly turned flange α adapted to be received by the slit 4 of the skirt preferably on the side facing the interior of the piston (Fig. 5),
- 10 the thickness of said flange (and of the walls of the filler tube) being less than, and approximately one-half the width of the slit 4 to allow for the necessary circumferential expansion of the skirt at high temperatures.
- 15 The filler tube 8 extends substantially the full length of the slit 4 (and its enlargement 4') and by the natural tendency of the metal of which said tube is formed to spring outward, it hugs the walls of the enlargements 4' when the piston is in service (Fig. 5). The filler tubes 8 serve to arrest the splashing (from the crank-case) of any oil through the slits 4 against the cylinder walls, and any oil that may find its way into the tube
- 20 through the relatively narrow passage between the flange α and the opposite wall of the slit by which it is received will simply run down the tube and be returned to the crank-case. The result is that any objectionable flow of oil past the lubricating surfaces of the piston into the combustion chamber is practically eliminated. The filler tubes likewise serve to impart rigidity to the skirt sections, thereby insuring a rigid
- 25 skirt under all working conditions and preventing side-slapping of the piston.
- In practice, the skirt portion of the piston is cast slightly oversize, that is to say, slightly larger than the bore of the cylinder,
- 30 after which the skirt is slit as shown, thereby imparting to the skirt sections between the slits a resilience which a skirt without the slits does not possess. After the skirt has been slit, the sections are slightly
- 35 sprung inward and held in this position by a suitable jig or band, and the piston placed in a lathe and turned true and finished smooth on the outside. When the skirt is released, the parts spring outward (dotted lines Fig. 2), so that when the piston is inserted into the cylinder the skirt hugs the walls thereof the full length of the slits.
- 40 While the skirt sections are free and outwardly sprung, the tubes 8 are inserted into the slit enlargements 4' through the open ends of the slits, the flanges α being preferably (though not necessarily) passed into the portions of the slits 4 on the side facing the interior of the piston (Fig. 5). When
- 45 the piston is inserted into the cylinder (the end carrying the piston rings 1 being inserted first through the end of the cylinder facing the crank-case, and pushed toward the end facing the combustion chamber E),
- 50 the outwardly sprung skirt sections gradu-

ally close over the filler tubes, causing a contraction or compression thereof against the tension of their outwardly sprung walls, the tubes thereby retaining their places in the slits under working conditions, the stiffness of the tubes preventing the skirt sections from yielding to the point where side-slapping is imminent. Obviously, with any rise in temperature the skirt sections will expand not only radially but circumferentially as well. The radial component is taken care of by the radial expansion of the walls of the cylinder, and the circumferential component is taken care of by the slits 4, the available widths of the slits between the flanges α and the opposite walls of the slits being sufficient to accommodate the maximum circumferential expansion that the skirt may undergo. When therefore the piston with its resilient filler tubes is once properly fitted into its cylinder, that fit is in no wise impaired with any rise in temperature, both components of the expansion which the skirt undergoes being taken care of, the skirt sections at all times maintaining their rigidity as a result of the support the same derive from the metallic tubular fillers 8. The pressure of the skirt sections against the walls of the cylinder is such that while the necessary quantity of oil is permitted to flow or pass between the piston and cylinder walls for maintaining the desired lubrication of the rubbing surfaces, no appreciable quantity of lubricant can find its way past the piston into the combustion chamber E. The rigid filler tubes 8 not only prevent any material yielding of the skirt sections with the diagonal pulls and thrusts of the connecting rod R during the rotation of the crank-shaft, but adjust themselves by their resilience to the expansions and contractions which the skirt sections undergo with changes of temperature, the pressure of the skirt against the walls of the cylinder remaining substantially uniform under all working conditions. The slits 4 while here shown as parallel to the axis of the piston may obviously be slightly inclined thereto without involving a departure from the nature or spirit of the invention.

Having described my invention what I claim is:

1. A piston for engine cylinders provided with a skirt slit or divided longitudinally, and longitudinally slit filler tubes in the slits of the skirt.
2. A piston for engine cylinders provided with one or more longitudinal slits open at the free end of the skirt of the piston, and longitudinally slit resilient filler tubes deposited in the slits of the skirt.
3. A piston for engine cylinders provided with a longitudinally slit skirt, the slits being open at the free end of the skirt, and suitable filler tubes mounted in the slits.

4. A piston for engine cylinders provided with a longitudinally slit skirt, the slits being open at the free end of the skirt, and suitable longitudinally slit filler tubes 5 mounted in the slits of the skirt, the slits of the tubes communicating with the interior of the piston skirt through the slits of the skirt.
5. A piston for engine cylinders provided 10 with a longitudinally slit skirt forming outwardly springing resilient members or sections between successive slits, and resilient longitudinally slit filler tubes inserted in said skirt slits.
- 15 6. A piston for engine cylinders provided with a skirt slit longitudinally and forming resilient outwardly springing members or sections between successive slits, the slits being formed with central tubular or cylindri-
- 20 cal enlargements, suitable longitudinally slit resilient filler tubes inserted in said enlargements, and outwardly turned flanges disposed along one of the longitudinal edges of the tubes adjacent the slits thereof received 25 by the slits of the skirt at points outside of and adjacent to the enlargements, said

flanges being of less thickness than the widths of the slits by which they are received.

7. A piston for engine cylinders provided 30 with a skirt slit longitudinally and forming resilient outwardly springing sections between successive slits, the slits being formed with medial tubular enlargements, longitudinally slit resilient metallic filler tubes inserted in said enlargements, and outwardly turned flanges disposed along one of the edges of the tubes adjacent the slits thereof received by the slits of the skirt at points outside of and adjacent to the enlargements 35 and facing the inside of the piston, said flanges being of less thickness than the widths of the slits by which they are received to allow for the necessary circumferential expansion of the skirt sections. 40 45

In testimony whereof I affix my signature, in presence of two witnesses.

CHARLES A. MARIEN.
